UNITED STATES PATENT OFFICE.

FREDERICK W. VAN BERGH AND GEORGE W. STYER, OF ROCHESTER, NEW YORK, ASSIGNORS TO THE VAN BERGH SILVER PLATE COMPANY, OF SAME PLACE.

DESIGN FOR A TEAPOT OR SIMILAR ARTICLE.

SPECIFICATION forming part of Design No. 34,159, dated March 5, 1901.

Application filed January 21, 1901. Serial No. 44,218. Term of patent 7 years.

To all whom it may concern:

Be it known that we, FREDERICK W. VAN BERGH and GEORGE W. STYER, citizens of the United States, residing at Rochester, in the county of Monroe and State of New York, have invented and produced a new and original Design for Teapots or Similar Articles, of which the following is a specification, reference being had to the accompanying drawings, forming a part thereof.

In the drawings, Figure 1 is a side elevation of a tea or coffee pot embodying our design. Fig. 2 is a cross-sectional view on the line $\alpha\alpha$ of Fig. 1.

15 The leading feature of our design is the shape and configuration of the body of a tea or coffee pot or similar containing vessel, which is equally applicable to other analogous articles usually embodied in tea-sets.

20 The article we have shown consists of a body, the lower portion of which (indicated by 1) is slightly larger in diameter at the upper edge 2 thereof, and at the lower edge is a band 3, supported upon ornamental legs 4. The sides

25 of the body 1 are ornamented with a series of oval or egg-shaped indentations or inwardly-curving depressions 5, forming be-

tween said portions ribs 6. The upper portion 7 of the body curves inwardly above the edge 2, gracefully flaring outwardly at its upper end, as shown, where it supports a top piece or cover 8. In the inwardly-curving portion of the part 7 are arranged a series of depressions 9, resembling slashes, which are located on lines between the oval or egg-shaped depressions 5 in the part 1. Ornamental shot-beading 10 is arranged, as shown, above the oval depressions 5 in the part 1, and a similar beading 11 extends around the upper edge of the top portion 7.

30 The essential part of the design being the particular shape or configuration of the body, we have shown the spout 12 and handle 13 in dotted lines.

Having described our invention, what we claim, and desire to secure by Letters Patent, is—

40 The design for a teapot or similar article substantially as shown and described.

FREDERICK W. VAN BERGH.
GEORGE W. STYER.
